UNITED STATES PATENT OFFICE

2,564,190

BATHTUB

Harry A. Danielson, Long Beach, Calif.

Application February 19, 1949, Serial No. 77,407

1 Claim. (Cl. 4—173)

1

My invention relates to the field of bathing devices, and more particularly to a bath tub adapted to be situated between adjoining walls with which it forms a water tight junction.

Although bath tubs have been known and used for a number of years, little or no improvement has been made in the manner in which a tub can be positioned between adjoining walls to form an integral part thereof, and at the same time to effect a waterproof junction therewith. In addition, the present day bath tub is not formed with handle means to assist a person in getting into or out of the tub, nor is it formed with a soap receptacle as an integral part of the tub structure.

As a result of the above mentioned disadvantages it is difficult to effect a waterproof joint between the adjoining walls and the tub. In addition an auxiliary soap holding receptacle must be installed which is not only expensive but is a constant danger inasmuch as a person may slip in the tub and strike the upwardly projecting soap dish. Also, in prior tubs a horizontal handle must normally be mounted on one of the adjoining walls to assist a person to get in or out of the tub, as well as providing a support for towels.

The applicant has found that due to the poor joint existing between the plaster on adjoining walls and the present day tub, water tends to seep inwardly therebetween with the result that the plaster becomes water soaked and tends to flake off and loosen from the supporting lath. Soap likewise accumulates at the junction line between the tub and plaster which results in a moist unsanitary area which is difficult to clean, and serves as an ideal place for germs and bacteria to breed.

The purpose of the applicant's present invention is to eliminate the disadvantages inherent to the present day bath tub, and to provide a tub which is safe to use and easy to install.

A major object of my invention is to provide a bath tub which can be installed between adjoining walls to form a water tight joint with the adjoining walls, will tend to decrease accidents occurring when a person enters or leaves the tub by providing a handle which can be grasped to assist this act, and has a non-projecting soap receptacle formed as an integral part of the tub which eliminates the possibility of injury to a bather should he slip or fall while in the tub.

Another object of my invention is to furnish a bath tub that can be installed at no greater expense than the present day bath tub, has an extremely simple construction, and will decrease the maintenance cost of a structure in which it is installed as there is no tendency for water or moisture to seep between the junction line of the tub and the adjoining walls.

A still further object of my invention is to reduce the cost of making a bath tub installation, in that, the soap receptacle is formed as an integral part of the tub which eliminates the neces-

2

sity of a separate soap receptacle being purchased and installed on one of the walls adjoining the tub.

These and other objects and advantages of my invention will become apparent from the following description of a preferred form thereof, and from the drawing illustrating that form in which:

Fig. 1 is a perspective view of my bath tub;

Fig. 2 is a vertical cross-sectional view of the device taken on the line 2—2 of Fig. 1;

Fig. 3 is a vertical cross-sectional view of the device taken on the line 3—3 of Fig. 1; and,

Fig. 4 is a fragmentary perspective view of the inner wall portion of the tub, and illustrating the manner in which a handle and soap receptacle are formed as an integral part thereof.

Referring now to Fig. 1 for the general arrangement of my invention, it will be seen that my bath tub B is substantially rectangular in shape, and has a continuous flange F extending upwardly from the ends and inwardly positioned side wall thereon. The bath tub B includes two interior end portions 10, an outwardly positioned side wall 11, and an inwardly positioned side wall 12. As is common practice in present day bathroom construction, the bath tub B is adapted to be installed in a recess formed in the walls W, with the walls being adjacent to both the ends 10 and the side 12 of the tub. Of course, should it be desired the tub B can be positioned in the corner of a bathroom rather than in a recess formed in the wall structure.

In Figs. 2 and 3 it will be seen that the sides 10, 11 and 12 are substantially vertically positioned, and formed from a metallic sheet material, with each of the sides terminating at the top thereof in a member 13. The member 13 can be either horizontal or inclined slightly inwardly towards the tub, and each of the members 13 developing into a substantially vertical flange F on the outer edge thereof. Each of the flanges F terminates on its upper edge in a substantially flat surface 14 that is adapted to come in contact with the plaster P which is applied to the wall W adjacent to that particular flange F. As a result of this construction as may best be seen in Figs. 2 and 3, the outer surface of the plastic P and the exposed surface of the flanges F are flush and in the same vertical plane.

Upon my tub B being installed on a bathroom floor (not shown) suitable bracing is placed under the bottom 16 of the tub in such a manner that when a person is sitting in the tub the increased weight will be equally distributed on the bottom 16. The tub B when installed in the above described manner will have no appreciable deflection when increased weight is applied thereto, with the result that the sheet metal members forming the tub are not deflected sufficiently to cause the enamel with which they are normally coated to crack and permit corrosion or rust to commence on the metal surface situated thereunder. In the event the en-

amel covering the sheet metal members is cracked, the enamel will start to loosen and peel therefrom in a relatively short time. Another reason to eliminate any appreciable downward movement of the tub B when a weight is applied thereto is to prevent the junction line between the plaster P and flanges F opening to admit water or moisture to the lath L and studing S situated therebehind which are shown in phantom lines in Figs. 2 and 3.

While I have mentioned the plaster P as the material which comes in contact with the upper edges of the flanges F, it will be apparent that the same advantage is obtained in effecting a waterproof joint between the flanges and engaging wall surface when the plaster P has conventional tile coating the outer surface thereof. When such a construction is used, the position of the tub with relation to the adjoining walls W must be such that the increased thickness of the plaster P and the tile coating same is compensated for to provide a vertical plaster surface that is flush with the flanges F.

The forward side 11 of the tub is the one which a person climbs over in getting into or out of the tub, and accordingly is not provided with one of the upwardly extending flanges F. Rather, the side 11 terminates in a substantially horizontal member 17 that on its forward edge is bent downwardly into a vertically positioned member 18. The lower edge of the member 18 is in the same horizontal plane as the downwardly positioned surface of the bottom 16 on which the tub B is supported.

A soap containing receptacle is provided in the upper central portion of the wall 12 by a recess 20 being formed therein. The recess 20 is provided with a longitudinally extending handle 21 of annular cross-section, with the recess so formed serving the dual purpose of providing a soap receptacle and handle means to assist a person in getting in or out of the tub. The recess 20 is rectangular in shape, and is preferably formed by bending a portion of the wall 12 and member 13 rearwardly to provide a vertical back member 22 and a rearwardly and downwardly sloping shell portion 23 on which the soap rests when it is positioned in the recess 20.

The outer edge of the shelf 23 is bent or curved downwardly to be brought smoothly into the substantially vertical side wall 12 which extends downwardly thereunder. Situated at each end of the recess 20 is a vertically positioned end piece 25 which is substantially rectangular in shape, and by a welding operation or other fastening means is joined to the end portion of the back member 22, the shelf 23, as well as the lower surface of one of the members 13 and the rearward surface of the wall 12.

The handle 21 is preferably fabricated from a tubular metallic stock, and is welded or otherwise secured to the end pieces 25 and extends longitudinally therebetween. Although the recess 20 is preferably formed by a stamping operation during the fabrication of the tub B, it will be apparent that it can also be formed by removing a portion of the tub and securing the back member 22 and shelf 23 to the tub to form the recess 20 should this be found desirable. While I have shown the recess 20 and handle 21 on the rearwardly positioned wall 12 of my tub, it will be apparent that this same type of handle and recess can be formed on the wall portion 11 in the same manner should it be so desired.

The installation and use of my invention is extremely simple. After the tub B has been installed in a bathroom, and plaster P applied to the adjacent walls W, a watertight junction is secured between the tub and plaster by bringing the plaster into contact with the upper edge 14 of the flanges. The plaster P is of such a thickness that the outer face thereof is flush with the exposed surface of the flange F it comes in contact with. Thus, there is no tendency for water to stand or seep through a junction line between the flanges F and the plaster P, as the water will flow downwardly along the exposed surface of the flanges to the members 13 on which it drains into the tub if these members are but slightly inclined inwardly.

The use of the device when installed is obvious. A person getting into or out of the tub B simply grasps the handle 21 in this operation, with the result that the person is braced should he start to fall or slip. The recess 20 simply serves to provide space where a bar of soap can be positioned on the shelf 23 in a conventional manner. Thus, a tub B is provided that is easy to maintain in a clean and sanitary condition as no water stands at or enters the junction line between the tub and the engaging plaster P, and as the handle 21 and soap receiving recess 20 are formed as an integral part of the tub they may be cleaned at the same time as the balance of the tub.

While the particular bath tub herein shown and described in detail is fully capable of attaining the objects and providing the advantages hereinbefore stated, it is to be understood that it is merely illustrative of the presently preferred form of my invention, and that I do not mean to limit myself to the details of construction or design herein shown other than as defined in the appended claim:

I claim:

A bath tub that includes: a substantially rectangular water holding shell formed from a sheet material; three substantially horizontal members extending outwardly from the upper edges of the ends and one of the longitudinal sides of said shell, with a portion of said longitudinally extending member and the side of said shell situated thereunder being formed into a downwardly and outwardly extending member of L-shaped cross section; two vertically positioned plates, with each of said plates affixed to one of the ends of the said member of L-shaped cross section and a longitudinal side of said shell to form a compartment in which soap may be positioned; and three flanges, with each of said flanges extending upwardly from the outer edges of said members, and the flange on said longitudinally extending member being in the same vertical plane as the longitudinally extending wall of said compartment.

HARRY A. DANIELSON.
